LIFE PRESERVER

Harry B. White, Wilmington, N. C.

Original application March 27, 1943, Serial No. 480,821. Divided and this application October 21, 1943, Serial No. 507,137

3 Claims. (Cl. 9—17)

This invention relates to new and useful improvements in life preservers, the same being a division of my co-pending application Serial No. 480,821, filed March 27, 1943, for Life saving apparatus.

The principal object of this invention is to provide a convenient means for supporting life preservers from the shoulders of the wearer with the assistance of foot stirrups, to the end that it is practically impossible for the life preserver to become detached from the wearer's body.

Other objects and advantages of the invention will become apparent to the reader of the following description.

In the drawings:

Figure 1 is a top plan view of the improved life preserver showing the body attaching means.

Figure 2 is a side elevational view of the preserver showing the shoulder straps and foot stirrups.

Figure 3 is a fragmentary detailed sectional view taken substantially on the line 3—3 of Figure 2.

Figure 4 is a sectional view taken substantially on the line 4—4 of Figure 2.

Referring to the drawings wherein like numerals designate like parts, it can be seen that numeral 5 denotes a life preserver annulus. In carrying out the present invention, shoulder straps generally referred to by numeral 6 are provided in cooperation with foot stirrups generally referred to by numeral 7.

The shoulder straps 6 each consists of a forward section 8 and a rearward section 9, each being bifurcated at its annulus attaching end to provide legs 10 which are attached to eyes 11 on the annulus 5. The remaining end of the section 9 has openings 12 through which the prong 13 of a buckle 14 on the complementary end of the section 8 is disposable. Obviously, this shoulder strap construction will be not only strong, but durable and capable of being readily adjusted.

The foot stirrups 7 each consists of an elongated strap 15, preferably endless and trained over the annulus 5 as shown in Figure 1. The lower portions of the flights of the endless strap 15 are brought together and secured as by riveting as at 16, thus defining a stirrup structure 17 which is completed by the provision of a plate 18 disposed within the stirrup loop and preferably secured thereto by a rivet or rivets 19.

Leg encircling straps 20 having buckles are provided on the stirrups 15 and preferably welded thereto as at 21 to prevent the leg from becoming displaced from the stirrup structure.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. A life saving apparatus comprising a floatable annulus, and foot stirrups depending from the annulus, each of said foot stirrups consisting of an endless strap disposed over the annulus and having its lower portion constricted to define a foot receiving loop.

2. A life saving apparatus comprising a floatable annulus, and foot stirrups depending from the annulus, each of said foot stirrups comprising an endless strap disposed over the annulus and having its lower portion constricted to define a foot receiving loop, and leg straps on said endless straps above said constricted lower portions.

3. A life saving apparatus comprising a floatable annulus, foot stirrups depending from the annulus, each of said foot stirrups comprising an endless strap disposed over the annulus and having its lower portion constricted to define a foot receiving loop, and rigid foot supporting plates in said loops riveted thereto.

HARRY B. WHITE.
